UNITED STATES PATENT OFFICE

CHARLES PICKER, OF ALBANY, NEW YORK

CLEANING MACHINE

Application filed October 22, 1926. Serial No. 143,483.

My invention relates to cleaning machines and particularly to a machine for cleaning floors.

The primary object of my invention is to provide a device of this character which will, in a single passage over a floor surface, not only remove and collect loose objects and particles of dirt, but wash and completely clean and dry the same. The invention contemplates either a self-propelled machine or a manually propelled machine which, as it progresses over the floor, first, picks up and collects comparatively large objects such as cigarette boxes, cigar butts, papers and the like; second, sweeps and collects all smaller particles of dirt and dust; third, moistens and scrubs the floor; fourth, mops and partially dries the floor; and fifth, completely dries the floor. Another object of my invention is to provide a means whereby the cleaning mechanism may be raised from the floor, and the device easily moved about in any direction by hand. Another object of my invention is to provide, in a machine of the general character, a means for sprinkling the floor in which a measured volume of water is delivered over a given area, and in which the sprinkling system is automatically cut off by the stoppage of the cleaning mechanism. Another object of my invention is to provide a means for conveying the dust and smaller particles of dirt swept from the floor, into a receptacle which is easily removed from the machine for dumping.

In attaining these and other objects, my invention includes the novel elements and combinations and arrangements of elements described below and illustrated in the accompanying drawings, in which—

Fig. 1 is a side elevation of my machine resting upon the wheels by which it is supported when moved about;

Fig. 2 is a plan view of my machine with the top covers and the water tank removed;

Fig. 3 is a longitudinal section of my machine in the broken plane 3—3 of Fig. 2;

Fig. 4 is an enlarged view of a detail of the mop tightening device and a partial section of Fig. 3 on the line 4—4;

Fig. 5 is an enlarged detailed view of the means for regulating the squeezing of the mop;

Fig. 6 is a section in the plane 6—6 of Fig. 2; 55

Fig. 7 is a section in the plane 7—7 of Fig. 2;

Fig. 8 is an enlarged fragmentary front view;

Fig. 9 is a partial sectional detail of a clutch mechanism;

Fig. 10 is a view of the clutch mechanism shown in Fig. 9 with the parts in a slightly different position;

Fig. 11 is a perspective view of a detail of the clutch mechanism; 65

Fig. 12 is an enlarged section in the plane 12—12 of Fig. 2 with certain parts removed;

Fig. 13 is an enlarged section in the plane 13—13 of Fig. 3; 70

Fig. 14 is a section of Fig. 12 in the plane 14—14;

Fig. 15 is a fragmentary enlarged section in the plane 15—15 of Fig. 3;

Fig. 16 is a view of the gears shown in Fig. 15, as viewed from the right hand side of Fig. 15; 75

Fig. 17 is similar to Fig. 16, but shows the gears in a different position;

Fig. 18 is an enlarged section in the plane 18—18 of Fig. 2; 80

Fig. 19 is a partial plan view of the portion shown in Fig. 18;

Fig. 20 is a detail of an element shown in Fig. 19; 85

Fig. 20A is a partial section of Fig. 18 in the plane 20A—20A;

Fig. 21 is an enlarged view in the plane 21—21 of Fig. 2;

Fig. 22 is a fragmentary enlarged view of 90 the rear end of the machine; and

Fig. 23 is a section of Fig. 22 in the plane 23—23.

Referring particularly to Figs. 1, 2, 3, 6 and 7, my machine comprises an outer case, 95 1, which may be closed at the top, if desired, by the hinged covers, 2, but which is open at the bottom. Within the outer case and secured thereto by a common plate, 3, at the front of the machine and between suitable 100

connecting members, 4, is an inner frame or case, 5, which is open both at the top and bottom. Within the inner frame and supported thereby are four separate tanks adapted to contain water, and numbered from the front of the machine towards the rear as, 6, 7, 8 and 9, respectively. The whole machine is supported upon four rubber tired wheels, 10, mounted on axles, 11, which may be provided with suitable bearings (not shown) in the sides of the inner casing, and which are provided with clutch mechanisms, 12, projecting through openings, 13, in the outer casing. The clutch mechanism is shown in detail in Figs. 9, 10 and 11 and will be described later. Mounted within the inner casing, and to the rear of the tank or reservoir, 9, is the electric motor, 14, which propels the machine over the floor. The motor, 14, turns the shaft, 15, through the bevel gears, 16, and the shaft, 15, turns the worm wheel, 17, through worm, 18, which coacts therewith. The worm wheel, 17, is mounted upon a transverse shaft which carries, at its other end, sprocket wheel, 19, coacting with a silent chain, 20. The connection between worm wheel, 17, and its shaft is controlled by a clutch mechanism, 12, similar in all respects to the clutch mechanism, 12, on the main wheels, 10. Fixed to the worm wheel shaft is a corrugated rubber roller, 21, adapted to carry the endless, drying mop, 22, which moves in the direction of the arrows shown in Fig. 3. The silent chain, 20, travels over sprocket wheels, 23, at the top, 24, at the bottom, and a sprocket wheel attached to the transverse shaft, 25, (see Fig. 3). The endless mop, 22, extends over and is driven by the corrugated roller, 21, and thereafter runs downwardly and around a corrugated rubber roller, 26, on shaft, 25; thence horizontally beneath the transverse rubber rollers, 27; thence upwardly around transverse rubber rollers, 28 and 29; thence downwardly, within tank, 8, and about the transverse tightening roller, 30; and thence upwardly between roller, 21, and the adjustable squeezing roller, 31. The pressure of the squeezing roll, 31, may be varied by the adjusting means, 32, shown in detail in Fig. 5. Referring to Fig. 5 the squeezing roll, 31, is mounted upon a shaft, 33, which is supported in bearing, 34. This bearing, 34, is provided with a longitudinally extending member, 35, passing loosely through the members, 36 and 37. The member, 36, is fixed to the longitudinal, threaded member, 38, passing loosely through the member, 37, which is riveted to the side of the case, 5, and which is provided with the adjusting nut, 39, abutting against the member, 37. A portion of the case, 5, about the adjusting nut, 39, is cut away and backward movement of the adjusting nut is prevented by its contact with the edge, 40, of the opening 65 in the case. Spring, 41, is provided which is

compressed between the member, 36, and the bearing, 34. From a consideration of the foregoing it will be apparent that by turning the nut, 39, the member, 38, and the member, 36, attached thereto, may be moved in a horizontal direction so that the compression on spring, 41, is varied. Thus, the pressure on the mop as it passes between rolls, 21 and 31, is varied.

The bearings of the shaft upon which the mop tightening roll, 30, is mounted, are carried by the vertical sliding bars, 42. These bars, 42, are adapted to slide vertically in the bearing members, 43, which are secured to the side of the case, 5.

Referring to Fig. 4 the rod, 42, is provided with a pin, 44, between which, and the bearing, 43, is compressed the spring, 45, tending to force the rod, 42, downwardly, thus keeping the mop, 22, under tension. The mop, 22, is held in contact with the floor by the action of the rollers, 27. These rollers are mounted upon transverse shafts running in bearings carried by the rods, 47, (see Fig. 7) which in turn are adapted to slide vertically in the bearings, 48, attached to the side of the case, 5. To insure that the mop will be kept in contact with the floor, springs, 49, compressed between the bearings, 47, and the bearings for the rolls are provided.

The sprocket, 23, which is driven by the silent chain, 20, is secured to a transverse shaft carrying a corrugated rubber roller, 50, driving the endless mop, 51. This mop moves in the same direction as mop, 22, and is carried about the main rollers, 52, 53 and 54. The mop, 51, is provided with a tightening roller, 30', a squeezing roller, 31', and rollers, 27', all similar to like numbered members associated with mop, 22. The squeezing roller, 31', is also provided with an adjusting means, 32', similar to the adjusting means, 32, for the squeezing roll, 31.

Fixed to each end of the shaft, 25, which is driven by the silent chain, 20, are gears, 55, meshing with gears, 56, secured to shaft, 11, upon which are mounted the rear propelling and supporting wheels.

The shaft which carries the rubber roller, 50, and is driven by sprocket, 23, carries, at its opposite end, a sprocket, 57, driving the silent chain, 58. The connection between sprocket, 57, and its shaft is controlled by a clutch mechanism, 12, similar in detail to the clutch mechanism, 12, on the main wheels. The chain, 58, extends downward, as shown in Fig. 7, and drives a sprocket wheel, 59, secured to the transverse shaft, 60, (see Figs. 2 and 3). Secured to each end of the shaft, 60, are the gear wheels, 61, which mesh with the gears, 62, secured to the shaft which carries the forward propelling wheels, 10. Thus, the propelling wheels, both front and rear, are driven by the motor, 14.

A gear wheel, 63, is also affixed to shaft, 60, and meshes with and drives gears, 64 and 65, (see Fig. 6). The gear, 64, drives the transverse shaft, 66, carrying the bevel gears, 67 and 68 (for details see Fig. 13). The bevel gears, 67 and 68, mesh with the pinions, 69 and 70, secured to the vertical, hollow shafts, 71 and 72, respectively. The vertical shafts, 71 and 72, are provided with the transverse bearing member, 73, at the top, and the bearing members, 74 and 75, at the bottom. Telescoping within the hollow shafts, 71 and 72, are the vertical rods, 76 and 77, respectively, which are secured to the angularly disposed scrubbing brushes, 78 and 79. The rods, 76 and 77, are adapted to be turned by the shafts, 71 and 72, respectively, by means of the screws, 80, which project through the slots, 81, as shown in the shaft, 71. The lower part of the hollow shafts, 71 and 72, are provided with pins, 82, between which, and the tops of the brushes are compressed the helical springs, 83. These springs tend to keep the brushes in contact with the floor.

The gear, 65, is mounted upon a short shaft which also carries the sprocket wheel, 84, and the bevel gear, 85, (see Fig. 12 for details). The gear, 65, meshes with the small pinion, 86, which drives the revolving brush, 87. This brush, as viewed in Fig. 3, revolves in a counterclockwise direction, is normally in contact with the floor, and brushes the dirt and dust from the floor into the transverse dustpan, 88. The dustpan, 88, is pivotally mounted in the sides of case, 5, as shown in Fig. 12, and the lower edge of the dustpan is normally kept in contact with the floor by means of the helical springs, 89, surrounding the axial mountings, 90.

Referring particularly to Figs. 8, 12 and 18, the bevel gear, 85, meshes with bevel gear, 91, mounted upon the longitudinal shaft, 92, which extends through the front end of the machine to receive gear wheel, 93. The gear, 93, meshes with and drives the gear, 94, on the forward end of the machine, and this gear drives the short shaft, 95, carrying sprocket wheel, 96. The sprocket wheel, 96, drives the silent chain, 97, which carries the dust conveyors, 98. The chain, 97, also runs over sprocket wheels, 99, 100 and 101, having fixed bearings, and over sprocket wheel, 102, mounted upon a vertical movable shaft, 103. The shaft, 103, may be moved up or down by means of the adjusting screws, 104 and 105, which are threaded through the shaft near its extremities, thus varying the tension on the dust conveyor chain.

The dust swept up by the revolving brush, 87, is carried up on the dustpan, 88, and falls over into the compartment, 106, (see Fig. 18). The dust conveyors, 98, passing beneath the inner end of the dustpan, 88, as shown in Fig. 3, catch most of the dust which is carried upwardly in the conveyors until they are in-

verted at the top as shown in Fig. 18. In this position the dirt falls downwardly, as shown in Fig. 3, and is collected in the drawer-like receptacle, 107, which may be withdrawn, as shown at 107', Fig. 3, and dumped. To prevent the dust from being thrown into the links of the conveyor chain, a thin guard plate, 200, is provided, which is riveted to the front plate, 3.

The sprocket wheel, 84, drives the silent chain, 108, which in turn drives a sprocket, 109, at the extreme front of the machine. The shaft, 110, to which the sprocket, 109, is attached, drives the front brush 111, through the crank, 112. The dotted circles, 111', and the dotted lines, 112', in Fig. 3, indicate different positions assumed by the brush and crank respectively. As the machine is propelled over the floor the eccentrically mounted brush, 111, revolves, as shown, and sweeps comparatively large objects into the forward scoop or dustpan, 113, which is hingedly connected to the front of the machine as at 114. To prevent the scoop from catching upon projections from the floor, it is supported on small rollers, 115, so that the front edge is raised slightly above the floor.

Referring particularly to Figs. 2, 3 and 13, I will now describe the automatic sprinkler means for moistening the floor after it is swept by the revolving brush, 87, and before it is scrubbed by the brushes, 78 and 79. Extending transversely of the machine, at a point comparatively near the floor and between the sweeping brush and the scrubbing brushes, is the perforated pipe, 116, connected to the small receptacle, 117, by the pipe, 118.

Referring now more particularly to Figs. 12, 15, 16, 17, 18, 19 and 20, for the particular details, and to Figs. 2 and 3 for the general assembly, the shaft, 119, which is driven by the dust conveyor chain through sprocket, 100, carries the segmental gear and cam, 120. Above, and slightly to one side of shaft, 119, is shaft, 121, mounted parallel to shaft, 119, and carrying the gear wheel, 122, adapted to mesh at certain times with the segmental gear, 120. The number of teeth in the segmental gear, 120, should be sufficient to revolve the dipper arm, 123, and dipper, 124, through the angular distance shown in Fig. 15. The dipper, 124, is simply a hollow cylinder provided with an opening, 125, in the top, through which water may enter when it is submerged, and which is connected through the hollow dipper arm, 123, to the shaft, 121. The shaft, 121, from its extremity within the receptacle, 117, to the point of connection of the dipper arm, 123, is hollow, as shown at 126, in Fig. 12 so that water may flow from dipper, 124, into receptacle, 117. The force of gravity assisted by the helical spring, 127, (see Figs. 2 and 3) tends to maintain the

125
130

dipper, 124, submerged in tank, 6. Projecting vertically into the bearing, 128, (see Fig. 18) of shaft, 121, is a screw, 129, the point, 130, of which projects into and forms a male unit coacting with the female, helical slot, 131, in shaft, 121, (see Fig. 20). As the machine is propelled over the floor, the segmental gear, 120, is turned rather slowly in the direction of the arrow shown in Fig. 15 and the teeth thereon engaged the teeth on gear, 122, thus turning shaft, 121, and raising the dipper, 124, full of water from tank, 6, to the position shown at 125' in Fig. 15. The water from the dipper flows down the hollow arm, 123, into the hollow shaft, 126, and out into the receptacle, 117, and thence through pipe, 118, to the sprinkler, 116. In order that the dipper, 124, may be held in the position shown at 124' in Fig. 15, for a sufficient length of time to empty the water therefrom into receptacle, 117, I provide the following described means. As the shaft, 121, is turned, the point of screw, 129, coacting with the helical slot in the shaft produces a longitudinal movement of the shaft, 121, tending to laterally disengage gears, 122 and 120. Referring to Figs. 15, 16 and 17, when the last tooth on the segmental gear, 120, has passed out of engagement with the teeth on gear, 122, the shaft, 121, has moved toward the front of the machine and occupies the position shown in Fig. 17. Here, the side of gear, 122, is frictionally engaged by the side of projecting rim, 132, of the segmental gear which holds the dipper in the position, 124' until the projecting rim, 132, has passed beyond the range of the side of gear, 122. To facilitate an easy transition of gear, 122, from the teeth on gear, 120, to the rim, 132, the edge of the rim, 132, adjacent the teeth is beveled, as shown at 133. By withdrawing the point of screw, 129, from its engagement with the helical slot, 131, in shaft, 121, the shaft, 121, may be pulled forwardly a sufficient distance by grasping knob, 134, to permanently disengage gears, 120 and 122, thus throwing the dipper out of operation.

Referring to Figs. 2 and 7, if for any reason the mechanism operating the dipper should break, I provide the valve, 135, operated by the hand wheel, 136, at the front of the machine for admitting water from tank, 6, to the sprinkler, 116, through pipe, 137 (see Fig. 7).

Suitably mounted upon the top of the machine is the water storage tank, 138, having a filling cap, 139, and provided, if desired, with a gauge, 140, adapted to indicate the quantity of water in the tank. The tank, 138, is provided with cocks, 141, 142 and 143 located respectively over tanks, 6, 7 and 8, whereby they may be readily filled with fresh water.

The tank, 9, is a drainage tank through which the dirt and water collecting in tanks,

7 and 8, may be drained through valves, 144 and 145. The tank, 6, may be drained through cock, 146, and the tank, 9, may be drained through valve, 147. The tanks, 7 and 8, are also directly connected to drainage tank, 9, through the overflow pipes, 201 and 202, respectively.

Figs. 9, 10 and 11, illustrate the details of the clutch mechanism, 12, by means of which each of the rubber tired wheels, 10, may be disengaged from its axle, the worm gear, 17, disengaged from its shaft, and the sprocket wheel, 57, disengaged from its shaft. Referring to these particular figures, 148, represents either one of the axles, 11, the shaft of the worm gear, 17, or the shaft for the sprocket, 57. 149, represents either the hub of one of the rubber tired wheels, 10, the hub of the worm gear, 17, or the hub of the sprocket, 57. Loosely mounted upon the end of the shaft, 148, is the manipulating button, 150. This button is hollow and is adapted to enclose the helical spring, 151, compressed between the washer, 152, on the end of shaft, 148, and the inside of the manipulating button, 150. The shaft, 148, is provided with the annular recess, 153, into which projects screw, 154, threaded into the hub of the wheel. The coaction of screw, 154, and recess, 153, prevents lateral movement of the wheel on the shaft but permits the wheel to rotate freely. The inner face of the manipulating button, 150, is provided with two projections, 155 and 156. The projection, 155, is adapted to coact with a complementary recess, 157, provided in the hub of the wheel, and the projection, 156, is adapted to coact either with a comparatively deep complementary recess, 158, in the shaft, (best shown in Fig. 9) or with a comparatively shallow complementary recess, 159, which is also in the shaft but spaced from recess, 158. When the parts are in the relative position shown in Fig. 9, projection, 156, is coacting with recess, 159, and the wheel may be turned independently of the axis. When the parts are in the relative position shown in Fig. 10, projection, 155, is coacting with recess, 157, in the hub, and projection, 156, is coacting with recess, 158, in the shaft thereby locking the wheel and shaft together.

Referring particularly to Figs. 1, 2, 18, 21, 22 and 23, in order that the cleaning mechanism may be easily raised from the floor, I provide near the front of the machine and at each side thereof wheels, 160 and 161, and at the rear of the machine a single, swivel-mounted wheel, 162. These wheels may be raised and lowered by the mechanism hereinafter described and by means of which the entire machine may be lifted off of the rubber tired wheels, 10, and be supported upon the wheels, 160, 161 and 162. Extending longitudinally of the machine and just within the outer case are the bars, 163, which are

pivoted to the outer case near the front and bottom thereof as shown at 164. These bars extend through the slots, 165, (see Figs. 21 and 22) in the rear of the outer case and 5 are connected at the rear end of the machine by the bar, 166. Near the pivots, 164, short vertical bars, 167, (see Fig. 18) are pivoted to the bars, 163, as shown at 168, and these vertical bars carry the axles, 169, for the 10 wheels, 160 and 161. These axles pass through vertically slotted openings in the outer case so that as the bars, 163, are moved vertically about the pivots, 164, the wheels, 160 and 161, are moved accordingly.

15 Referring now more particularly to Figs. 21, 22 and 23, secured to the bar, 166, is a plate, 170, provided with two depending portions, 171, having rollers, 172, at their lower extremities adapted to roll against the rear 20 of the outer case. Supported upon the upper side of the depending portions, 171, are bearings, 173, which carry the U shaped rod, 174. The extremities of the rod, 174, are pivoted within the clevises, 175, and these clevises 25 are, in turn, connected with the bolts or latches, 176, which extend through bar, 166. Secured to the rear of the casing, and adapted to coat with the bolts or latches, 176, are the racks, 177. Secured to the U shaped bar, 30 174, at its center, is the foot pedal, 178, which may be depressed to withdraw the extremities of the bolts or latches from the racks, 177. The foot pedal, 178, is normally held in the position shown in Figs. 22 and 23 by the 35 tension spring, 179, so that the latches are normally held engaged with the racks. On account of the shape of the rack teeth it will be obvious that the plate, 170, with its attached parts may be moved downwardly 40 without releasing the engagement of the latches and racks, thus moving the bars, 163, downwardly about their pivoted extremities and lowering the wheels, 160 and 161. To 45 raise the bars, 163, it will be necessary to depress the pedal, 178, so that the latches are disengaged from the racks.

The rear end of the outer case, at its center, is provided with a vertical slot, 180. 50 Resting against the outer rear side of the casing, and adapted to slide vertically relative to said casing is the plate or bar, 181, to which is attached the wheel, 162, swiveled at 182. The bar, 181, is held in sliding engagement 55 with the rear end of the outer case by the bolts, 183 and 184, which pass through the rear end of the casing.

Pivoted to the inner rear side of the outer casing, as shown in Figs. 21 and 23 are the 60 arms, 185. Pivoted to the arms, 185, are the cross-arms, 186, pivotally connected together, where they cross, by the bolt, 184, and pivotally connected at the top by the transverse bar, 187. It will be apparent from a 65 reference to Fig. 21 that the bars, 163, rest

upon and are normally supported by the transverse bar, 187.

When the plate, 170, is forced downwardly, it also forces the transverse bar, 187, downwardly and this in turn forces the 70 wheel, 162, downwardly by the coaction of the cross-bars, 186, and the bolt, 184. When the parts are in the relative position shown in Figs. 22 and 23, the transverse bar, 187, will be in the position indicated by 187', the 75 cross-bars in the position indicated by 186', the bars, 185, will move outwardly to the position indicated at 185', and the bars, 163, will be moved downwardly to the position indicated by 163'.

When the parts are in the relative position shown in Figs. 22 and 23, the propelling wheels, 10, will be lifted from the floor and the machine will rest upon the outside, forward wheels, 160 and 161, and the swiveled, 80 rear wheel, 162. It will be obvious that when the machine is supported on these wheels the cleaning mechanism is lifted from the floor and the swiveled supporting wheel at the rear will permit the device to be readily swung 85 about in any direction.

While I have shown no controlling mechanism for the electric motor, nor any connections therefor, it is to be understood that 90 such controlling mechanism and connections 95 may be provided at any convenient point.

In operation, my machine may be propelled over the floor by the electric motor which is operatively connected to the driving 100 associated with each wheel, or it may be propelled by hand through the handles, 188. When propelled by hand, the clutches, 12, associated with the wheels, 10, are adjusted to the position shown in Fig. 9, so that the 105 wheels, 10, may turn freely on their axles. In this latter case, the cleaning mechanism may still be operated by the electric motor provided the clutch, 12, associated with the worm gear, 17, is left engaged.

110 In comparatively small machines or in machines which embody a portion only of the cleaning mechanism disclosed in my complete device, or in other case, it may be desired to both propel the machine and operate the cleaning mechanism by hand. In this case, the motor may be dispensed with and the driving wheels, 10, adapted to turn the axles to which they are affixed, thus driving the cleaning mechanism. Where it is desired to 115 both propel and drive the cleaning mechanism of a motor equipped machine, such as herein described, by hand, the clutches, 12, associated with the wheels, 10, may be adjusted so that the wheels will drive the axles, 120 and the worm wheel, 17, may be disconnected from its shaft by the clutch, 12.

125 As it progresses, comparatively large objects such as cigar butts, wads of paper, etc., are caught by the eccentrically mounted 130

brush, 111, and swept into the scoop, 113. Where such an object is intercepted by the front edge of the scoop and the brush, 111, is in one of the positions shown at 111', in Fig. 3, the object will be pushed along the floor by the edge of the scoop until the brush approaches the position shown in 111, whereupon the object will be swept into the scoop. The brush, 87, revolves at comparatively high speed so that the fibers thereof in contact with the floor move toward the dustpan, 88. The dust is carried up over the dustpan and falls into the driven conveyor where it is carried upwardly and dropped into the dirt receptacle, 107. When the dust is removed from the floor by the brush, 87, the floor is immediately sprinkled with water. It is important to note here that when, for any reason the progress of the machine is stopped, the dipper, 124, will cease to operate and no water will be delivered to the sprinkler. After the floor is sprinkled, it is thoroughly scrubbed by the revolving brushes, 78 and 79, which turn at comparatively high speed in contact with the floor. This operation loosens all dirt which may be adhering to the floor and which was not picked up by the brushes, 111 and 87, but leaves the dirty water on the floor. Following the scrubbing process is the first mop, 51, which moves in the direction of the arrow shown in Fig. 3 and is held in contact with the floor by the spring depressed roller, 27'. This mop effects a rough drying operation absorbing most of the water and dirt which is carried upwardly into tank, 7. The tank, 7, is kept partially full of water which washes the dirt from the mop as it passes through, and the excess water in the mop is removed by the squeezing roll, 31'. Following the first mop is the second mop, 22, which practically completes the drying operation, and the dirt collected by this mop is washed out and deposited in tank, 8, and the surplus water removed from the mop by the action of the squeezing roll, 31.

The dustpan, 88, is provided with a rather sharp lower edge, and inasmuch as this edge is normally held in contact with the floor by the springs, 90, it might be seriously damaged or even torn from the machine by any backward movement thereof. For this reason I have provided the ratchet wheel, 189, (see Figs. 12 and 14) which is mounted on the shaft carrying sprocket wheel, 84, gear wheel, 65, and bevel gear, 85. Pivotedly secured to the side of the case is the pawl, 190, which is held in operative engagement with the teeth of the ratchet by spring, 191. The coaction of the pawl and ratchet will prevent backward movement of the machine.

From the foregoing it will be apparent that I have provided a machine which will, in one passage over a given surface of floor completely clean the same. It is to be understood, however, that I am not limited to the

precise details herein described and illustrated in the drawings, nor to a machine performing all of the functions herein set forth. For example, a machine having only a front scoop with an eccentrically mounted brush for collecting comparatively large objects would be valuable apart from any other elements, and the combination of an eccentrically mounted brush coacting with a scoop for collecting large objects, and a rotating brush for collecting dust, would form a sweeping machine of some considerable value. In other words, many subcombinations of elements described and illustrated would, in themselves, prove extremely useful. It is therefore to be understood that the words which I have used in describing my invention are words of description rather than words of limitation, and that changes within the purview of the appended claims may be made without departing from the true scope and spirit of my invention.

What I claim is—

1. In a floor cleaning machine of the character described, the combination with means for collecting comparatively large objects and comprising a revolving brush and means for periodically elevating from and lowering the brush to the floor, of means for collecting small particles of dirt and comprising a revolving brush in continuous contact with the floor and behind said first mentioned brush.
2. In a floor cleaning machine including a reservoir adapted to contain water, the combination with means for propelling said machine, of a sprinkler pipe adapted to spray water over the floor, and a dipper, oscillated by the propelling means, for dipping water from the reservoir and delivering it to the sprinkler.
3. In a floor cleaning machine, the combination with a tank adapted to contain water, of a movable dipper adapted to raise water from said tank, a sprinkler head communicating with said dipper, and means for raising said dipper from and lowering it into said tank including means for sustaining said dipper in raised position to discharge the water therein to said sprinkler.
4. In a floor cleaning machine, the combination with a tank adapted to contain water, of a horizontal hollow shaft above said tank, a dipper normally submerged in said tank and spaced from but communicating with said hollow shaft through a hollow arm connecting the two together, a gear on said hollow shaft, a second shaft having a segmental gear thereon coacting with said first mentioned gear, and means for driving said last mentioned shaft to periodically raise the dipper from the tank.
5. In a floor cleaning machine, the combination with a tank adapted to contain water, of a movable dipper adapted to raise

water from said tank, and means for raising said dipper from said tank; said last mentioned means including means for temporarily sustaining said dipper in raised position.

5 6. In a floor cleaning machine, the combination with a plurality of tanks adapted to contain water for washing the dirt from a plurality of belt mops driven through said water, of a tank adapted to receive the drainage from said first mentioned tanks, and a tank adapted to contain a supply of fresh water for replenishing said first mentioned tanks by gravity.
